UNITED STATES PATENT OFFICE

2,090,155

MACHINE FOR USE IN MAKING BOXES

Alfred L. Rosenmund, Rockaway, N. J., assignor
to Stapling Machines Co., a corporation of
Delaware

Application October 25, 1934, Serial No. 749,873

15 Claims. (Cl. 140—93)

This invention relates to machines for equipping wired box parts with fastening means, and particularly to machines for manipulating a wire secured to a box part to form and perpetuate a bight on the end of the wire.

It is an object of the invention to provide certain improvements in a machine of the type disclosed in U. S. Patent to Rosenmund No. 1,933,031.

It is a further object to provide such a machine with improved means for positioning the box part relative to the wire-manipulating elements to locate the fastening means a predetermined distance from the box part edge.

It is a further object of the invention to provide such a machine with safety means adapted to prevent an operation of the machine unless the box part is correctly positioned for a wire-manipulating operation.

It is a further object of the invention to provide a safety device of the character referred to which is controlled by the position of the box part, thus insuring a correct location of the fastening means relative to the box part.

One illustrative embodiment of the invention is shown in the accompanying drawings, in which:—

Figure 1 is a perspective view of a pair of wire connected box blanks upon which the machine is designed to operate.

Fig. 2 is a perspective view of a box blank after it has been operated upon by the machine of this invention and showing the character of fastening means supplied by the machine.

Fig. 3 is a perspective view of a completed box formed by folding the blank of Fig. 2 into box form about end sections and interengaging the fastening means.

Fig. 4 is a diagrammatic view of the wire-manipulating elements of the machine and showing in dotted lines the initial position of the wire-connected box blanks on their supporting table prior to a wire-manipulating operation and, in full lines, the position of the box parts and the supporting table when they have been lowered to present the wires to the wire-manipulating elements.

Fig. 5 is a top plan view of the supporting table with certain parts left out to disclose more clearly the box part positioning means.

Fig. 6 is an enlarged top plan view of one of the box positioning devices in operative position.

Fig. 7 is a similar view showing the positioning device in its non-operative position to permit the removal of the completed box part after a wire-manipulating operation.

Fig. 8 is a side elevation of the foot pedal for operating the clutch to throw the machine into operation and showing the safety device for preventing operation of the pedal except when the box part is in correct position relative to the wire-manipulating elements.

Fig. 9 is an enlarged detail showing the cam means for moving the positioning devices to non-operative position after a box blank has been correctly positioned relative to the wire-manipulating elements.

Referring to Fig. 1, the machine of this application is intended to receive on a supporting table the wire-connected box parts designated A and B and to sever the connecting wires designated C, form prongs on the severed ends, swing the prongs over onto the box parts to form bights, and to drive the prongs into or through the box parts to perpetuate the bights. The completed bights thus formed are shown in Fig. 2 and designated D.

When the blank shown in Fig. 2 is folded into box form as shown in Fig. 3, the fasteners D may be passed one through the other and hooked to complete the continuity of the wire binding.

As shown in Fig. 4, the wire-connected box parts A and B when fed into the machine are positioned on a table or support 1, which is adapted to be lowered to present the connecting wires C to the wire-manipulating elements.

It is desirable that the box parts A and B be correctly located or positioned before the wires C are presented to the wire-manipulating elements. This is accomplished by definitely positioning the front edge of the box part B prior to starting the machine. Definitely positioning the box part B also definitely positions the box part A, because the length of the wires connecting the two box parts are of definite predetermined length. Thus, when the box part B is definitely positioned relative to the wire-manipulating elements, the length of the connecting wire will definitely position the box part A.

To definitely position the forward edge of the box part B relative to the wire-manipulating elements, stop mechanism is provided which normally lies in the path of travel of the box part B and arrests movement of the box part B when the box part strikes the stop mechanism and moves it to the limit of its travel. After the box part has been definitely positioned against the stop mechanism and the machine started, the stop mechanism is withdrawn from in front of the box part and held in non-stop position during a wire-manipulating operation. The stop mecha-

nism of this invention will be described in detail hereinafter.

Associated with the stop mechanism and controlled thereby is a safety mechanism for preventing operation of the machine except when the box part is properly positioned for a wire-manipulating operation. This safety device will also be described in detail hereinafter.

When the box parts have been correctly positioned on the supporting table 1, the machine may be started by throwing into operation a one-cycle clutch. When the machine is started the table 1 is lowered to present the connecting wires C to the wire-manipulating elements which sever the wires to form prongs on the severed ends, swing the prongs over onto the box parts, and drive the prongs into or through the box parts.

The wire-manipulating elements and their operation are fully shown and described in the aforementioned patent to Rosenmund No. 1,933,031, reference to which patent is hereby made for a detailed description.

The improved stop mechanism for positioning the box parts relative to the wire-manipulating elements is best shown in Figs. 5, 6 and 7. Referring to Fig. 5, which shows in skeleton form the table or support 1 upon which the box parts rest and the stop mechanism of this invention associated therewith, the forward edge of the incoming box part is positioned by contacting with stops 2 located on each side of the incoming box part and extending into the path of travel of the box part to be engaged thereby.

The stops 2 are each pivotally and adjustably mounted on an arm 3, the arms 3 being pivotally mounted on brackets 4 secured to one of the table cross bars 5. Stops 2 are each normally held in the position shown in Fig. 5 by springs, the right hand stop in Fig. 5 being held in normal position by a spring 6, one end of which is secured to the stop 2, and the other end of which is attached to a portion of the arm 3, while the left hand stop is held in normal position by a spring 7, one end of which is secured to the bracket 4 and the other end to a rod 8 pivotally connected to the outer end of the stop 2. Pivotal movement of the stops 2 on the arms 3 is controlled by pins 9 carried by the stops and which engage the arms 3 at either extreme of the movement of the stops 2.

The upper ends of arms 3 carrying the stops 2 are urged toward each other by springs 10. Such movement is limited by adjustable stops 10a carried by brackets 4 and which engage the lower ends of arms 3.

The upper ends of arms 3 carrying the stop 2 are moved away from each other by cam plates 11 (see Fig. 9) which contact with rounded cam surfaces 12 on the arms 3 when the table 1 is lowered to present the box parts and the connecting wires to the wire-manipulating elements. The cam plates 11 are adjustably secured to a stationary part of the machine directly beneath the cam surfaces 12 of the arms 3 so that when the table 1 is lowered the arms 3 will be swung away from each other, i. e., from the position of the arm 3 shown in Fig. 6 to the position of the arm 3 shown in Fig. 7.

Still referring to Fig. 5, when a box part is fed into the machine its forward edge contacts with the stop members 2 and pushes the stop members 2 forward against the action of the springs 6 and 7 until the pins 9 contact with the arms 3 and prevent further movement of the stop members 2. When in this position the

box part is correctly positioned for a wire-manipulating operation. Both stop members 2 are then in the position of the stop member shown in Fig. 6, i. e., in contact with the forward edge of the box part. When in this position the table 1 is lowered, causing the cam plates 11 to swing the arms 3 away from the box part to the position of the arm 3 shown in Fig. 7.

When the wire-manipulating operation is completed, the table 1 rises, thus permitting arms 3 to pivot toward the box part under the influence of springs 10. At this time, however, the stop members 2 (under the influence of springs 6 and 7) occupy the pivoted position of the stop member 2 shown in Fig. 7, so that when the stop members swing toward the box part they engage the side of the box part and drag along the side of the box part while it is being withdrawn from the machine. When the completed box part has been drawn past the stop members 2, the springs 10 move the arms 3 inwardly and the stop members 2 are moved into the path of the next oncoming box part in position to engage the front edge of that oncoming box part and position it for the next machine operation.

The safety mechanisms for preventing operation of the machine except when a box part is correctly positioned relative to the wire-manipulating elements is best shown in Figs. 6, 7 and 8. As shown in Fig. 6 the rod 8 which is pivotally connected at one end to the outer end of the pivoted stop member 2 will be moved by pivotal movement of the stop member 2. The other end of the rod 8 is adjustably and pivotally fastened to a lever 13 which is pivotally mounted on a cross member 14 of the table 1 (see Fig. 8).

Referring to Fig. 8, the lever 13 is rigidly fastened to a sleeve 15 by means of a rod 16 and pins 17. Slidably mounted in the sleeve 15 is a square rod 18, the lower end of which is rounded to permit rotation in a bearing 19 carried by a bracket 20 fastened to the base of the machine. Fixed to the rod 18 by means of a pin 21 is a casting 22 carrying on its upper surface a lug 23.

Journaled in bearings in the bracket 20 is a shaft 24, which when rotated in a clockwise direction throws into operation the one-cycle clutch to cause the wire-manipulating elements to go through one complete cycle of operation. Fixed to the shaft 24 is a casting 25, shaped as shown in Fig. 8 to provide foot pedal 26 and an upwardly extending portion 27. Pivotally mounted on the upper end of the upwardly extending portion 27 is a latch 28 carrying a hook 29 which extends beyond the lug 23 carried by the casting 22 and rests upon the upper surface of the casting 22.

Referring to Figs. 6 and 7, the casting 22 is fan-shaped and lug 23 is located on the upper surface of the casting 22 near one of its side edges. When the lug 23 is in the position shown in Fig. 7, the latch 28 will prevent foot pedal 26 from being depressed. On the other hand, when the lug 23 is moved from the position shown in Fig. 7 to the position shown in Fig. 6, the foot pedal 26 may be depressed. The casting 22 and its lug 23 are moved from the position shown in Fig. 7 to the position shown in Fig. 6 by the incoming box part which engages and moves the positioning device 2 about its pivot point, i. e., from the position shown in Fig. 7 to the position shown in Fig. 6. This pivotal movement of the positioning device 2 moves the rod 8 and through the link 13 and the rod 18 the casting 22 with its lug 23, from the position shown in Fig. 7 to the posi-

tion shown in Fig. 6. Thus, the machine can only be started when the box part has contacted and moved the positioning device to the position shown in Fig. 6. When the arm 3 has been swung away from the box part by the cam plate 11, as hereinbefore described, the spring 7 will return the casting 22 and its lug 23 to the position shown in Fig. 7.

Among other advantages this invention provides a dependable means for correctly positioning a box part for a wire-manipulating operation, and also provides a safety mechanism associated therewith to prevent operation of the machine unless the box part is correctly positioned relative to the wire-manipulating elements.

It will be understood that the invention is not to be limited to the specific embodiment shown for purposes of illustration, as the inventive features of the machine may be used in other forms.

It will also be understood that all of the inventive features need not be used conjointly, as they may be used in various combinations as defined in the subjoined claims.

25 I claim:

1. In a machine of the character described, the combination of wire-manipulating mechanisms to form and perpetuate a bight on a wire secured to a box part, a vertically movable support for the box part, and means to position the box part relative to said mechanisms, said positioning means including a pivotally mounted stop member yieldingly held in the path of the incoming box part, and a fixed cam member to swing the stop member out of the path of the box part when the support descends.

2. In a machine of the character described, the combination of wire-manipulating mechanisms to form and perpetuate a bight on the end of a wire secured to a box part, a vertically movable support for the box part, and means to position the box part relative to said mechanisms, said positioning means including a stop member yieldingly held in the path of the incoming box part, and a fixed cam member to swing the stop member out of the path of the box part when the support descends.

3. In a machine of the character described, the combination of wire-manipulating mechanisms to form and perpetuate a bight on the end of a wire secured to a box part, a vertically movable support for the box part, and means to position the box part relative to said mechanisms, said positioning means including a pair of stop members yieldingly held in the path of the incoming box part, and fixed cam members to swing the stop members out of the path of the box part when the support descends.

4. In a machine of the character described, the combination of wire-manipulating mechanisms to form and perpetuate a bight on a wire secured to a box part, a vertically movable support for the box part, and means to position the box part relative to said mechanisms, said positioning means including a pivotally mounted arm, a stop member pivotally mounted on the swinging end of said arm, spring means to move the arm and stop toward the box part, means to move the arm and stop away from the box part, and means yieldingly to hold the stop member in a predetermined relationship to the arm.

5. In a machine of the character described, the combination of wire-manipulating mechanisms to form and perpetuate a bight on a wire secured to a box part, a vertically movable sup-

port for the box part, and means to position the box part relative to said mechanisms, said positioning means including a pivotally mounted arm, a stop member pivotally mounted on the swinging end of said arm, spring means to move the arm and stop toward the box part, and means to move the arm and stop away from the box part.

6. In a machine of the character described, the combination of wire-manipulating mechanisms to form and perpetuate a bight on the end of a wire secured to a box part, a support for the box part, means to cause relative movement between the support and said mechanisms to present the box part to the operation of said mechanisms, and means to position the box part relative to said mechanisms, said positioning means including a stop member yieldingly held in the path of the incoming box part, and a cam member to swing the stop member out of the path of the box part upon relative movement between the support and said mechanisms.

7. In a machine of the character described, the combination of wire-manipulating mechanisms to form and perpetuate a bight on the end of a wire secured to a box part, means to position a box part relative to said mechanisms, and means controlled by said positioning means to control the operation of said mechanisms.

8. In a machine of the character described, the combination of wire-manipulating mechanisms to form and perpetuate a bight on the end of a wire secured to a box part, means to position a box part relative to said mechanisms, and means controlled by said positioning means to prevent operation of said mechanisms unless the box part is in correct position to be operated upon thereby.

9. In a machine of the character described, the combination of wire-manipulating mechanisms to form and perpetuate a bight on the wire of a box part, movable means to position a box part relative to said mechanisms, and means controlled by movement of said positioning means to control the operation of said mechanisms.

10. In a machine of the character described, the combination of wire-manipulating mechanisms to form and perpetuate a bight on the wire of a box part, and box part positioning means movable by pressure of a box part thereagainst to control the operation of said mechanisms.

11. In a machine of the character described, the combination of wire-manipulating mechanisms to form and perpetuate a bight on the wire of a box part, means to position a box part relative to said mechanisms, and means controlled by the position of the box part to control the operation of said mechanisms.

12. In a machine of the character described, the combination of wire-manipulating mechanisms to form and perpetuate a bight on the wire of a box part, means to position a box part relative to said mechanisms, and means to prevent operation of said mechanisms until the box part is in correct position to be operated upon by said mechanisms.

13. In a machine of the character described, the combination of wire-manipulating mechanisms to form and perpetuate bights on a wire connecting two box parts, a support for the box, means to cause relative movement between the support and said mechanisms, and means to position the box parts relative to said mecha-

nisms, said positioning means including a stop member yieldingly held in the path of an incoming box part, and a cam member to swing the stop member out of the path of the box part upon relative movement of the support and said mechanisms.

14. In a machine of the character described, the combination of wire-manipulating mechanisms to form and perpetuate bights on a wire connecting two box parts, means to position the box parts relative to said mechanisms, and

means controlled by said positioning means to control the operation of said mechanisms.

15. In a machine of the character described, the combination of wire-manipulating mechanisms to sever a wire connecting two box parts and to form a bight on each severed end, means to position the wire-connected box parts relative to said mechanisms, and means controlled by said positioning means to control the operation of said mechanisms.

100 ALFRED L. ROSEN MUND.
